UNITED STATES PATENT OFFICE.

OLIVER E. BARTHEL, OF DETROIT, MICHIGAN.

ENGINE HEAD.

Application filed August 9, 1922. Serial No. 580,596.

This invention relates to a cylinder head for air cooled engines, and has special reference to a cylinder head that may be cast in block form and advantageously used on a 5 multiplicity of cylinders inclosed so as to receive a blast of air from a motor driven fan, fly wheel or the like or air that may impinge against and pass through a radiator of an automobile or other vehicle equipped 10 with an air cooled engine and cylinder head in accordance with this invention.

One of the objects of my invention is to provide a cylinder head with a fuel intake gallery or chamber which permits of an incoming 15 charge of fuel to cool the engine head, the gallery or chamber having a single entry with a continuous flow of fuel in diverging direction therein and by having exhaust chambers extending through the intake gallery or chamber, the incoming charge 20 of fuel will have a cooling effect on the exhaust chambers.

Another object of this invention is to provide an engine head with an intake gallery 25 or chamber in which heavy particles of an explosive mixture may be vaporized and placed in a better condition for combustion, the intake gallery or chamber being subjected to heat by conduction and walls of the 30 gallery or chamber are shaped to cause any fuel condensate to drain away from the intake ports and allow for revaporization.

A further object of this invention is to furnish a cast cylinder head with fire and heat 35 resisting inserts adapted to increase the longevity of the head and afford valve seat members which will insure a positive seating of intake and exhaust valves associated with the head.

40 A still further object of this invention is to furnish a cast cylinder head with heat disseminating ribs or vanes, some of which are integral with the head and others of which are anchored in the head during the casting 45 thereof.

The above are a few of the objects obtained by a mechanical construction to be hereinafter described, and reference will now be had to the drawings, wherein

50 Figure 1 is a top plan of the engine head; Fig. 2 is a side elevation of the head, partly in section;

Fig. 3 is a bottom plan of the head;

Fig. 4 is a horizontal sectional view taken on the line IV—IV of Fig. 2; 55

Fig. 5 is an end view of the cylinder head as applied to an air cooled engine;

Fig. 6 is an enlarged end view of the engine head;

Fig. 7 is an enlarged cross sectional view 60 of the engine head taken on the line VII—VII of Fig. 1;

Fig. 8 is a similar view taken on the line VIII—VIII of Fig. 1,

Fig. 9 is a similar view taken on the line 65 IX—IX of Fig. 1, and

Fig. 10 is a detail sectional view of a portion of a water cooled engine showing a driven fan for forcing air downwardly between the engine cylinders. 70

The engine cylinder head is cast en bloc to form an oblong intake gallery or chamber 1 having a bottom wall 2, a top wall 3, and side and end walls 4. The length of the chamber depends upon the number of cylinders to be served thereby. 75

The chamber bottom wall 2 has its lower face formed with depending cylindrical combustion chambers 5 corresponding in number to the cylinders on which the head is mounted, for instance a six cylinder engine, and the lower edges of the combustion chambers 5 have lateral apertured flanges 6 by which the head may be bolted or otherwise firmly secured to a cylinder block. 85

The spaced combustion chambers 5 are connected by flanged webs 7 forming air ducts or passages 8 communicating with casings 9 in the chambers 1, said casings connecting the walls 2 and 3 to form vertical air 90 ducts or passages through the chamber 1, said casings having the upper and lower ends thereof open at the walls 2 and 3, so that air may pass downwardly through the engine head and between cylinders 10 of an air 95 cooled engine 11.

At one side of the cylinder head the combustion chambers 5 have lateral openings or sockets 12 for spark plugs, and fixed in the top of each combustion chamber 5, are metallic inserts 13 in the form of disks, each having a pair of valve seat openings 14 and 15 for intake and exhaust valves. These metallic inserts are made of a high heat resisting 100

material of a more indurate nature than the metal from which the cylinder head is cast, and said metallic inserts are of a greater diameter than the combustion chambers 5 so that the marginal edges of the inserts may be anchored and made integral with the head during the casting thereof.

The intake valve seat openings 14 communicate with openings 16 in the bottom wall 2 of the chamber 1 and said chamber, intermediate its ends, has another bottom wall opening 17 communicating with a fuel intake connection 18, best shown in Fig. 9, said fuel intake connection being between two of the combustion chambers 5. This fuel intake connection 18 may be suitably connected to a carburetor to supply vaporized fuel to the gallery or chamber 1 and from this gallery or chamber the vaporized fuel is adapted to pass through the openings 16 and 14 into the combustion chambers 5, when the intake valves are opened.

The top wall 3 of the gallery or chamber 1 has valve rod guides 19 coaxial of the openings 14 and 16 for overhead valve rods 20, which as shown in Fig. 5, may be actuated by rockers 21 supported by brackets 22 attached to apertured bosses 23 on a side wall 4 of the head, preferably the intake side of said head.

The exhaust valve seat openings 15 communicate with openings 24 in the chamber wall 2 and with angularly disposed exhaust conduits 25 extending through the chamber 1 and terminating in large tubular bosses 26 on the chamber wall 3 and to which an exhaust manifold 27 may be suitably connected. The tubular bosses 26 include valve rod guides 28 coaxial of the exhaust valve seat openings 15.

In the gallery or chamber 1 are a multiplicity of tubular bosses 30, some of which adjoin the casings 9 and others adjoin the side and end walls 4 of the chamber. These bosses are disposed co-axially of similar bosses 31 on the top wall 3 of the chamber 1 and bosses 32 connecting the bottom wall 2 of the chamber to the apertured flanges 6 of the combustion chambers 5, thus permitting of screw bolts or nut equipped bolts being used to fix the head relative to the cylinders 10.

On the top wall 3 of the gallery or chamber 1 are longitudinally disposed parallel heat disseminating vanes or ribs 33, some of which extend over the upper open ends of the casings 9, others connecting tubular bosses and valve rod guides on the wall 3, and other vanes or ribs being of less depth than the remaining vanes or ribs, as best shown in Figs. 6 and 8, so that connections can be easily made with the tubular exhaust bosses 26.

The wall 4 of the gallery or chamber 1, at the spark plug side of said head, may be

provided with vane or rib inserts 34 disposed in parallelism and preferably made of aluminum, said inserts being anchored and made integral with the wall 4 during the casting thereof.

The air cooled engine 11 has a hood or casing 35 provided with a horizontal partition 36 supporting sleeves 37 about the cylinders 10 of the engine. The partition 36 cooperates with the hood in forming a longitudinal passage 38 about the cylinder head and this passage may be connected to a radiator receiving a blast of air or the passage 38 may receive a blast of air from a fan or fly wheel. In either instance, such blast of air impinges against the cylinder head and the vanes or ribs thereof to carry off such heat as may be radiated from the cylinder head. The air will enter the casings 9 and ducts 8 and pass downwardly between the cylinders 10 of the engine, these cylinders being provided with fins or vanes as indicated in Fig. 5. The air also passes through the sleeves 37 and circulates within the lower part of the hood due to the action of the engine fly wheel in said hood or at one end thereof.

As a further instance of means contributing towards the circulation of air about the engine cylinders, I show in Fig. 10 a horizontally disposed fan 40 mounted on the vertically disposed fan shaft 41 having a worm gear 42 driven by a worm 43 on an overhead cam shaft 44 which is ordinarily employed for operating overhead valves. With a driven fan over each cylinder and said fans inclosed by a suitable casing 45 air may be driven downwardly into the sleeves 37 and between the fins on the cylinders 10 of the engine. These fans alone, or in co-operation with other suitably placed fans, will insure a circulation of air about the engine cylinders.

Reference will again be had to Figs. 4, 7 and 9 showing the upper face of the chamber bottom wall 2 to have a longitudinal central ridge or surface slanting towards the side walls 4. Any unvaporized fuel or condensate within the gallery or chamber 1 will eventually accumulate on the bottom wall 2 and since this all is subjected to heat, by conduction from the cylinder block, the liquid fuel will be vaporized before it is carried out of the gallery or chamber into the combustion chambers 5. Because of the exhaust conduits 25 extending through the gallery or chamber 1 it is obvious that incoming vaporized fuel will impinge against the walls of these conduits be heated, and placed in better condition for deterioration in the combustion chambers 5 by spark plugs extending therein, and while the cylinder head is primarily designed as a heater for vaporized fuel, yet it serves for disseminating heat and may be readily cooled

in connection with an engine of the air cooled type.

It is thought that the utility of the cylinder head will be apparent without further description, and while in the drawings there is illustrated a preferred embodiment of my invention, I desire it to be understood that the cylinder head may be modified for use on air cooled engines other than that diagrammatically shown, furthermore, that my invention is not limited other than defined by the appended claims.

What I claim is:—

1. An engine head for a six cylinder engine, said head having combustion chambers therein for the engine cylinders and a fuel chamber in a plane above said combustion chambers with the bottom wall of said fuel chamber ported to communicate with said combustion chambers, exhaust conduits extending from the bottom wall of said fuel

chamber to the top wall of said fuel chamber and the bottom wall of said fuel chamber inclined downwardly and outwardly from its longitudinal middle portion to cause any liquid fuel to drain to opposite sides of said fuel chamber, said exhaust conduits and the ports thereof being in a central longitudinal plane of said head, and a fuel intake connection for said fuel chamber.

2. An engine head as called for in claim 1, wherein said fuel intake connection is in the horizontal plane of said combustion chambers and communicates with said fuel chamber at the bottom wall thereof and between the centralmost combustion chambers.

3. An engine head as called for in claim 1, and air passage casings between the endmost pairs of combustion chambers and extending through said fuel chamber.

In testimony whereof I affix my signature.

OLIVER E. BARTHEL.
